UNITED STATES PATENT OFFICE.

FRED C. STORRS, OF CHICAGO, ILLINOIS.

SAWING-MACHINE.

No. 847,845.

Specification of Letters Patent.

Patented March 19, 1907.

Application filed May 1, 1905. Serial No. 258,253.

To all whom it may concern:

Be it known that I, FRED C. STORRS, a citizen of the United States, residing at Chicago, county of Cook, and State of Illinois, have 5 invented certain new and useful Improvements in Sawing-Machines, of which the following is a full, clear, and exact specification.

My invention relates to that type of sawing-machines in which the saw is pivotally 10 mounted on a standard adapted to be clamped to the log, while the saw is free to swing; and the invention has for one of its objects to provide the saw with improved means for causing it to feed automatically in either a vertical 15 or a horizontal position.

Another object of the invention is to so construct and improve the machine that it may be readily folded into a compact form for transportation; and a still further object 20 of the invention is to make the saw-frame adjustable, so that it may not only be folded, but may be utilized for holding blades of different lengths.

With a view to the attainment of these 25 ends and the accomplishment of certain other objects which will hereinafter appear the invention consists in the features of novelty which will now be described with reference to the accompanying drawings and 30 more particularly pointed out in the claims.

In the said drawings, Figure 1 is a side elevation of my improved sawing-machine, showing the same applied to a log. Fig. 2 is an enlarged detail plan view of the feeding-nut and mechanism hereinafter described. 35 Fig. 3 is a side elevation of the machine, and Fig. 4 is a vertical section taken transversely of the saw-blade. Fig. 5 is a perspective view of the swinging cross-head or lever.

1 is the saw-blade, which is preferably curved on the arc of the circle in which the blade swings or reciprocates, and it is detachably secured by pins or bolts 2 in the lower ends of two arms 3 4, which are pivoted 45 adjacent to each other by their upper ends to a swinging cross-head or lever 5, which latter is provided with ears or lugs 6, the centers of which form the center of the arc or radius upon which the saw-blade 1 is curved 50 and swings, and said lugs or ears serve as a pivotal support for the saw-frame thus constituted. Arranged between the arms 3 4 are two toggles 7 8, which are hinged or pivoted together at 9, while one of them is 55 hinged at 10 to the arm 3, and the other one is pivoted at 11 to the arm 4. The toggle 8

is provided near its inner end with an eye 12, to which is secured the upper end of a rod 13, connected at its lower end to a turnbuckle 14, which is screw-threaded on the upper end 60 of a rod 15, secured at its lower end by an eye 16 to the arm 3, whereby the proper manipulation of the turnbuckle 4 will tighten or loosen the saw-blade, as desired, or will adjust the arms 3 4 to adapt them for blades of various lengths.

The lugs or ears 6 of the cross-head or lever 5 are pivoted by a pin 17 to an arm 18, which latter depends from a collar 19, and this collar has swivel connection 20 with a nut 21, 70 composed of two members hinged together, as shown at 22, Fig. 2, and provided with a dog or latch 23 for holding them together. This nut 21 is screw-threaded on a screw 24 and is provided around its upper edge with 75 ratchet-teeth 25, with which engages a pawl 26, mounted on the upper end of an arm 27, attached to the side of the cross-head or lever 5, so that as the saw frame or arms 3 4 are oscillated on the pivots 17 the pawl 26 will be 80 caused to engage the teeth 25 and rotate the nut 21, thus feeding the latter downwardly on the screw 24 and causing the saw-blade to feed into the log. The screw 24 at its upper and lower ends is mounted upon a main 85 standard 28 by means of suitable brackets 29, so as to be fixed with relation to the saw-frame and the nut. The lower end of the standard is formed with a foot 30, which is laterally extended on one side of the standard 90 and provided with spurs 31, adapted to be driven into the log, while the other side or standard may have a guide-block 32, against which the saw-blade runs when being started into the log.

At or near the upper end of the standard on both sides are vertical series of holes or sockets 33 for the insertion of hooks or lugs 34, formed on the upper ends of the guy-rods. One of these rods, the one shown at 35, 100 may be a plain rod with a spur 36 at its lower end adapted to be driven into the log, while the other one is composed of two sections 37 38, connected together by turnbuckle 39, the lower one having a spur 40 at its lower end 105 adapted to be driven into the log, so that by tightening the turnbuckle 39 the standard 28 may be rigidly clamped to the log in either a vertical or a horizontal position, and in either position the nut and screw will serve to feed 110 the saw to the limit of its maximum cutting depth, and when that depth is reached it may

be retracted and the nut moved to the upper end of the screw by raising the clasp 23 and sliding the frame and collar 21 upwardly or outwardly.

5 When desired, the machine may be folded together in knocked-down form by removing one of the pins or bolts 2 and folding up the blade 1 with the arms 4 the pin 11 having been previously withdrawn, and one end of the turnbuckle 14 detached from the toggles 7 8, allowing them to fold up lengthwise with the arm 3, whereby all parts, including the guy-rods, will arrange themselves longitudinally of the main standard.

15 When the machine is to be used in a horizontal position, it may be supported at one end of the standard 28 by an adjustable support composed of telescopic members 28^a 28^b, secured to standard 28 by hinge 28^c, and 20 having a set-screw 28^d for binding them together.

Having thus described my invention, what I claim as new therein, and desire to secure by Letters Patent, is—

25 1. In a sawing-machine the combination of a saw-blade, a saw-frame comprising arms secured at their lower ends to the blade and pivotally connected together at their inner ends, toggle-arms secured to one of the first 30 arms and removably engaging the other arm for connecting the first said arms together, means for operating said toggle-arms to move the first said arms toward and from each other, a standard, and means pivotally 35 supporting said saw-frame upon the standard.

2. In a sawing-machine the combination of a standard, a saw-frame comprising two arms

having their inner ends arranged contiguous to each other and pivotally supported upon the standard, a saw-blade removably secured 40 to the outer ends of said arms, and a cross-brace removably secured between said arms, whereby the said machine may be folded up.

3. In a sawing-machine the combination of a standard, a saw-frame comprising two arms having their inner ends arranged contiguous to each other and pivotally supported upon the standard, a saw-blade removably secured to the outer ends of said arms, a hinged cross-brace, one end of which is pivoted to one of the arms, the other end removably engaging the other arm, and adjustable means engaging one of the sections of the cross-brace and the adjacent arm, for varying the position of the arms. 55

4. In a sawing-machine the combination of a standard, a saw-frame comprising two arms having their inner ends arranged contiguous to each other and pivotally supported upon the standard, a saw-blade removably secured to the outer ends of said arms, a hinged cross-brace, one end of which is pivoted to one of the arms, the other end removably engaging the other arm, a rod pivotally connected to one section of the brace, a second rod pivoted to the adjacent arm and a turnbuckle connecting the free ends of the rods for varying the position of the brace members to adjust the arms. 60 65

FRED C. STORRS.
